ROLLER COTTON GIN.

No. 499,560.

Patented June 13, 1893.

UNITED STATES PATENT OFFICE.

FREDERICK L. MONTGOMERY, OF NEW YORK, N. Y.

ROLLER COTTON-GIN.

SPECIFICATION forming part of Letters Patent No. 499,560, dated June 13, 1893.

Application filed November 17, 1892. Serial No. 452,322. (No model.)

To all whom it may concern:

Be it known that I, FREDERICK L. MONTGOMERY, of the city, county, and State of New York, have invented a new and Improved 5 Roller Cotton-Gin, of which the following is a full, clear, and exact description.

The object of the invention is to provide a new and improved roller cotton gin, which is simple and durable in construction, very effective in operation and arranged to quickly and thoroughly strip the seed from the lint of any grade cotton, without danger of tearing or pulling the fibers apart.

The invention consists of a drum, and two rollers held in peripheral contact with the drum, and of which one serves as a knife roller to strip the seed from the lint and the other serves to hold the lint to the drum while the seed is removed.

The invention also consists of certain parts and details, and combinations of the same, as will be hereinafter described and then pointed out in the claims.

Reference is to be had to the accompanying drawings, forming a part of this specification, in which similar letters of reference indicate corresponding parts in all the figures.

Figure 1 is a plan view of the improvement with parts in section. Fig. 2 is a sectional side elevation of the same on the line 2—2 of Fig. 1. Fig. 3 is an end view of the same with parts broken out. Fig. 4 is a rear side elevation of the machine. Fig. 5 is an enlarged front view of the knife roller and its bearings with parts in section. Fig. 6 is a transverse section of the same on the line 6—6 of Fig. 5. Fig. 7 is a similar view of part of the same on the line 7—7 of Fig. 5. Fig. 8 is a side elevation of one of the bearings for the knife rollers. Fig. 9 is a sectional elevation of one of the bearings for the knife rollers; and Fig. 10 is a side elevation of the gearing for driving the knife rollers.

The improved roller cotton gin is provided with a suitably-constructed frame A, on which is supported a hopper B, containing the cotton to be ginned, the cotton passing onto a feed drum C extending into the bottom of the said hopper and secured on a shaft C' journaled in suitable bearings on the main frame A. On one end of the shaft C' is se-

cured a pulley C², over which passes a crossed belt C³, also passing over a pulley C⁴ secured on the main driving shaft D provided with the usual fast and loose pulley E connected by belt with suitable machinery for imparting a rotary motion to the said shafts D and C'. The feed drum C has the usual roughened peripheral surface to properly feed the cotton from the hopper B.

In the front of the hopper B is formed an opening B', directly above the periphery of the drum C, so that the cotton can readily pass out of the hopper to be carried by the revolving drum C onto a transversely-extending feed table F inclined rearwardly and discharging at its lower end onto the periphery of the ginning roller G, secured on the main driving shaft D. A second feed table F' is arranged transversely between the ginning roller G and the drum C, so as to prevent any cotton from being carried to one side and not onto the ginning roller G.

The ginning roller G is provided with a solid core G' made of wood or other suitable material, and having a covering G² of leather, canvas or other elastic material. On the periphery of this covering G² are held two rollers H and H' of which the roller H is a knife roller to separate the seed from the lint, while the other roller H' located below the first roller H, but close to the same, serves to press the lint to the drum covering G² during the time the seed is removed by the other roller H.

The rollers H and H' are made in the shape of shafts of small diameter extending the entire width of the ginning roller G, and each roller bearing is formed in sections J' fitted to slide in a recess J² extending transversely in a bar J³ yieldingly mounted and adapted to be raised and lowered, as hereinafter more fully described.

Each section J' of the bearing J is pressed on at its under side by a spring J⁴ resting with its ends on the said bearing and engaged at its middle and at the under side by a setscrew J⁵ screwing in the bar J³. This set screw serves to increase or diminish the tension of the spring J⁴ to press the section J' with more or less force against the knife roller H or H', so as to hold the latter in proper contact with the ginning roller G. The rollers H must

necessarily be small to prevent the seed from passing through, and as a small roller is liable to spring it must be supported throughout its length. As shown in Figs. 6 and 7, a 5 hard rubber block or plate J^6 may be interposed between the spring J^4 and the respective section J' for the roller H' , to make the latter less yielding than the roller H .

The rollers H and H' are journaled in boxes 10 J^7 and J^8 formed on the ends of the bar J^3 . The boxes J^7 and J^8 are formed on their under side with screw threads, each engaged by a screw K formed on a sleeve K' fitted to slide over a hollow pin K^2 formed on the head K^3 15 of a screw K^4 , screwing in a nut K^5 attached to or formed on the legs of the frame A . A spring K^6 set in the hollow pin K^2 presses on the sleeve K' so as to force the latter upwardly with the bar J^3 to hold the rollers H 20 and H' in peripheral contact with the ginning roller G . Now, it will be seen that by turning the screws K^4 the tension on the springs K^6 is increased or diminished, according to the direction in which the screws are 25 turned, so that the bearing J for the rollers H and H' , is forced up with more or less force to hold the rollers H and H' with more or less pressure in contact with the peripheral surface of the ginning roller G .

30 It is understood that the rollers H and H' are supported between the boxes J^7 and J^8 , on the bearing sections J' , so that each roller is prevented from spreading and is held uniformly against the peripheral surface of the 35 ginning roller G throughout the entire length. The enlarged end of the roller H passing through the box J^8 carries a pinion L in mesh with a gear wheel L' journaled on a suitable bracket L^2 held adjustably on the main frame 40 A , as illustrated in Fig. 4. This gear wheel L' is in mesh with an internal gear wheel N secured on the main driving shaft E , so that when the latter is rotated the internal gear wheel N will revolve the gear wheel L' , and 45 the latter the pinion L , so as to turn the roller H in the same direction in which the ginning roller G revolves. The gearing is so proportioned that the roller H revolves at a much higher rate of speed than the ginning roller 50 G to readily separate the seed from the lint, when the latter is drawn downward between the drum and roller H . The other roller H' is geared with the roller H and in order to 55 revolve the second roller in the proper direction, a gear wheel L^8 on the roller H' meshes into an intermediate gear wheel L^4 held on the bearing J^7 and gearing into the gear wheel L^5 secured on the roller H' . See Figs. 5 and 60 10. As shown in Fig. 5 the intermediate gear wheel L^4 is sufficiently wide to engage both gear wheels L^8 and L^5 .

In front of the roller H directly below the lower feed table F is arranged a discharge table I , extending downwardly and forwardly, 65 so that the seed removed from the lint by the knife roller H passes over the feed table F' onto the said discharge table I to be delivered

to one side of the machine. The lint adhering to the drum covering G^2 after leaving the rollers H , H' , after the seed is stripped off, is 70 finally removed from the said drum covering G^2 by a stripper cylinder O , acting as a brush, and provided with a core O' secured on a transversely-extending shaft O^2 , journaled in suitable bearings on the main frame A . One 75 end of this shaft O^2 carries a pulley O^3 , over which passes a belt O^4 , also passing over a pulley O^5 secured on the main driving shaft D . On the core O' of the stripper cylinder O are secured transversely-extending radial 80 blades O^6 made of sheet metal or other suitable material and adapted to reach with their outer edges, close to the peripheral surface of the ginning roller G , to take the lint off the said stripper cylinder when the machine is in 85 operation.

The operation of the machine is as follows: When the main shaft D is rotated, the feed drum C revolves in the direction of the arrow a' , the ginning roller G in the direction of the arrow b' , and the stripper cylinder O in the direction of the arrow c' . Now, the cotton from the hopper B is carried by the feed drum C onto the feed tables F and F' and onto the revolving ginning roller G , which carries the 95 cotton downward and between it and the roller H which prevents the seed from passing through so that the seed is finally stripped off from the lint and passes over the discharge table I down to one side of the machine. 100 During this stripping operation of the seed the second roller H' presses the lint at its thickest part onto the ginning roller G , the roller H , then being at the thinnest part of the cotton, that is on the end carrying the seed, 105 as will be readily understood by reference to Fig. 6. The lint still adhering to the covering G^2 is carried upward and removed by the blades O^6 of the stripper cylinder O , which latter causes the lint to drop in a continuous 110 fleece into a suitable box P extending rearwardly from the main frame A .

As illustrated in Fig. 6, each bearing section J' engages about one half of the roller H or H' , so that by the several sections, the roller 115 is held always in proper position, especially as each section can be adjusted by the corresponding set screw J^5 as above described. By this arrangement, the seed is prevented from passing between the ginning roller G and roller 120 H , without being removed, as the roller can be adjusted to press uniformly with more or less force against the peripheral surface of the ginning roller G . The yieldingly mounted boxes carrying the rollers H , H' , permit a 125 heavier or lighter bunch of cotton to pass between them and the ginning roller G , but will prevent any seed from passing the same way.

It is well known that a flock of cotton is thickest at the middle and thinnest at the 130 ends, one of the ends carrying the seed to be removed. Now, by the arrangement of the rollers H and H' , the cotton passing between the said rollers by the drum is engaged by

the roller H' at or near the middle at the thickest part, while the other roller H engages the cotton near the end at the thinnest part or in the neck at the seed so that by the pull exerted on the second roller H' on the heavier part of the cotton, the seed is readily removed from the end without stretching the fiber between the two rollers.

With this machine, upland cotton can readily be ginned, as the seed cannot pass between the roller H and ginning roller G, without being removed from the staple.

Having thus fully described my invention, I claim as new and desire to secure by Letters Patent—

1. A roller cotton gin provided with a drum, a knife roller held in peripheral contact with the said drum and journaled in a bearing composed of sections arranged one alongside the other throughout the contact length of the said roller with the said drum, and a spring for each bearing section to hold the latter in contact with its part of the roller, substantially as shown and described.

2. A roller cotton gin comprising a drum and two rollers located one in front of the other and held in peripheral contact with the said drum throughout the width of the same, one of the said rollers serving as a knife roller to separate the seed from the lint, while the other roller holds the lint at its thickest part to the drum during the time the seed is removed by the first roller, substantially as shown and described.

3. A roller cotton gin comprising a drum, a knife roller held in peripheral contact with the said drum, a bearing for the said roller and extending throughout the length of the same, the said bearing comprising bearing sections, and a bar in which the said sections are independently and yieldingly mounted, substantially as shown and described.

4. A roller cotton gin comprising a drum, a knife roller held in peripheral contact with the said drum, a bearing for the said roller and extending throughout the length of the same, the said bearing comprising bearing sections, a bar in which the said sections are independently and yieldingly mounted, and a spring for each independent bearing section to hold the latter to its part of the roller, substantially as shown and described.

5. A roller cotton gin comprising a drum, a knife roller held in peripheral contact with the said drum, a bearing for the said roller and extending throughout the length of the same, the said bearing comprising bearing sections, a bar in which the said sections are

independently and yieldingly mounted, and means, substantially as described, for yieldingly supporting the said bar, as set forth.

6. A roller cotton gin comprising a drum, a knife roller held in peripheral contact with the said drum, a bearing for the said roller and extending throughout the length of the same, the said bearing comprising bearing sections, a bar in which the said sections are independently and yieldingly mounted, means, substantially as described, for yieldingly supporting the said bar, and means for revolving the said roller at a higher rate of speed than the said drum, substantially as shown and described.

7. A roller cotton gin, comprising a drum having an elastic covering, a knife roller held in peripheral contact with the said drum, yielding bearing sections engaging the said roller, a second roller held in frictional contact with the said drum below the said first named knife roller, and yielding bearing sections for the said second roller, substantially as shown and described.

8. A roller cotton gin comprising a hopper, a feed roller for carrying the cotton from the said hopper, feed tables onto which discharges the said feed drum, a ginning drum having an elastic covering and onto which discharge the said feed tables, a knife roller in frictional contact with the said elastic covering, a second roller in peripheral contact with the said ginning drum and arranged below the first named knife roller, and yielding bearings for the said rollers, substantially as shown and described.

9. A roller cotton gin comprising a hopper, a feed roller for carrying the cotton from the said hopper, feed tables onto which discharges the said feed drum, a ginning drum having an elastic covering and onto which discharge the said feed tables, a knife roller in frictional contact with the said elastic covering, a second roller in peripheral contact with the said ginning drum and arranged below the first named knife roller, yielding bearings for the said roller, and a stripping cylinder acting as a brush and provided with transversely-extending and radially-arranged blades made of steel or other metal and extending with their outer edges close to the periphery of the said ginning drum, substantially as shown and described.
